UNITED STATES PATENT OFFICE.

CHARLES BRYANT MACDOUGALL, OF SEATTLE, WASHINGTON.

DESIGN FOR A LIGHTING BOWL.

Application filed December 12, 1925. Serial No. 15,729. Term of patent 3½ years.

To all whom it may concern:

Be it known that I, CHARLES BRYANT MACDOUGALL, a citizen of the United States, residing at Seattle, in the county of King and State of Washington, have invented a new, original, and ornamental Design for Lighting Bowls, of which the following is a specification, reference being had to the accompanying drawing, forming part thereof.

The figure is an elevation of a lighting bowl, showing my new design.

I claim:

The ornamental design for a lighting bowl as shown.

Seattle, Washington, November 18, 1925.

CHARLES BRYANT MACDOUGALL.
